(57) **CLAIM**

The ornamental design for a retractable floor lamp, as shown and described.

DESCRIPTION

FIG. 1 is a perspective view of a retractable floor lamp, showing my new design.

FIG. 2 is a front view of a retractable floor lamp.

FIG. 3 is a rear view of a retractable floor lamp.

FIG. 4 is a left side view of a retractable floor lamp.

FIG. 5 is a right side view of a retractable floor lamp.

FIG. 6 is a top view of a retractable floor lamp.

FIG. 7 is a bottom view of a retractable floor lamp.

FIG. 8 is a perspective view of a retractable floor lamp, showing in a stretched state; and,

FIG. 9 is a perspective view of a retractable floor lamp, showing in another stretched state.

The broken lines in the drawings depict portions of the retractable floor lamp that form no part of the claimed design.
